CAPPING MACHINE

Abraham Podel, New York, N. Y., assignor to
 Anchor Cap & Closure Corporation, Long Island
 City, N. Y., a corporation of New York

Application September 19, 1931, Serial No. 563,701

28 Claims. (Cl. 226—87)

The present invention relates more particularly to a sealing machine for band caps and the like, but certain features of the invention are applicable, also, to other types of sealing machines.

Glass containers vary in size by as much as several inches, and to a less extent in diameter. In addition, due to limitations of the machinery for manufacturing glass containers, the containers vary from a true standard both in size, height and roundness. The permissible irregularities have been definitely prescribed by the Glass Container Association, but in selecting and inspecting the ware, it is not always possible to 10 keep within the prescribed variations. A satisfactory commercial sealing machine should, therefore, be capable of accommodating a wide range of sizes of containers both in height and diameter. In addition, it should be readily 15 adjustable for these different sizes without requiring skilled labor and without requiring substantial time in making the change. In sealing band caps, the lower edge of the skirt is rolled under a shoulder on the glass container. The metal 20 is rolled directly against the glass. It is particularly important, therefore, that irregularities in the glass be taken care of by the machine without occasioning breakage or undue strain on the container. Breakage not only causes loss 25 of the package and its contents, but also loss of time in stopping the machine and cleaning up the broken glass and the contents of the package.

The present invention aims to provide an improved sealing machine which eliminates, or greatly minimizes, the above difficulties by providing a very secure seal on containers varying a maximum amount from the prescribed standard and by providing a machine readily adjustable for various sizes of ware, both in height and diameter. The present embodiment of the machine will readily take care of bottles or jars ranging from two and one-half to ten inches in height, and from 45 one to three and seven-eighths inches in diameter. It will be understood that greater or less ranges in size of containers can be accommodated by extending the principles of the invention. The adjustment for various sizes is simple 50 and may be readily made by unskilled operators. The present invention also aims to simplify the construction of the machine and to minimize the cost thereof without sacrificing the advantages obtained.

55 An object of the present invention is to provide

an inexpensive sealing machine adapted to seal containers more effectively and efficiently than machines heretofore.

Another object of the invention is to increase the speed of sealing caps to containers, and to 5 simplify the mechanical and manual operations heretofore required.

Another object of the invention is to provide a sealing machine adapted to reform the skirt of a cap upon a container, which can be readily 10 adjusted to accommodate caps and containers of various sizes.

Another object of the invention is to provide a sealing machine which is particularly adapted 15 for sealing band caps upon containers.

A further object of the invention consists in the combination of elements and arrangement of parts adapted to achieve the objects enumerated above.

Other and further objects of the invention will 20 be obvious upon an understanding of the illustrative embodiment about to be described, or will be indicated in the appended claims, and various advantages not referred to herein will occur to one skilled in the art upon employment of the 25 invention in practice.

A preferred embodiment of the invention has been chosen for purposes of illustration and description and is shown in the accompanying drawings, forming a part of the specification, 30 wherein

Fig. 1 is a side elevational view partly in section, illustrating a preferred embodiment of the invention;

Fig. 2 is an enlarged elevational view of the up- 35 per portion of the machine shown in Fig. 1;

Fig. 3 is a sectional view taken along line 3—3 of Fig. 2;

Fig. 4 is an enlarged sectional view taken along the line 4—4 of Fig. 3, illustrating the cam operating clutch;

Fig. 5 is a sectional view taken along the line 5—5 of Fig. 1, illustrating the means for positioning the containers upon the sealing table;

Fig. 6 is an enlarged sectional view taken along the line 6—6 of Fig. 3, showing the gear members for operating the spinning rollers;

Fig. 7 is an enlarged sectional view taken along the line 7—7 of Fig. 3, illustrating spinning rollers and their supports;

Fig. 8 is a fragmentary side elevational view, partly in section, illustrating a cap being sealed upon a container;

Fig. 9 is an enlarged perspective view illustrating a preferred mechanism for operating the seal- 55

ing means, certain parts being omitted for simplicity; and

Fig. 10 is a fragmentary disclosure of a modified construction for adjusting the movement of the 5 spinning rollers.

Briefly described, the machine illustrated herein comprises a suitable base upon which the various parts are mounted and a column extending upwardly therefrom. A table adapted to support the containers during the sealing operation is secured to the column. Above the table there is provided a sealing head which is operatively connected to the supporting column and is adapted to move vertically. The sealing head comprises suitable spinning rollers which are adapted to move radially into and out of effective position at desired intervals, and are operated in timed relation by a suitable mechanism operatively connected to the main drive by means of 10 gears and cam devices. For operating the machine, there is provided a foot pedal adapted to make the cam devices effective, and a hand lever adapted to control the driving means.

As shown in the preferred embodiment of the 25 invention, the spinning rollers are adapted to constrict the lower edge of the skirt of a cap about a suitable shoulder on a container. This is effected by placing the cap upon a container, pressing it downwardly thereon, and then moving 30 the spinning rollers upwardly and inwardly into engagement with the lower edge of the cap. When band caps are used, as shown herein, the lower edge of the band is spun inwardly beyond the sealing zone of the container to hold it securely thereon. The present machine may be utilized for various other spinning operations.

Referring again to the drawings, and more particularly to Figs. 1, 2 and 3, there is shown a machine having a base 1 formed from a suitable casting 40 adapted to be bolted to the floor or other suitable foundation. At the center of the base, there is provided a vertical column 2 mounted upon the base and having a shaft 4 extending upwardly therein and rotatably mounted upon a 45 suitable ball bearing 5 supported by member 6 attached to the base portion 1. At the upper end of the column 2, a top portion 7 is provided, and a cylindrical casting 9, having a flange 10, is bolted thereto. The casting 9 is provided with a 50 pair of internal bushings 11 adapted to receive the shaft 4 to hold it rotatably in position with respect to the column 2.

Any suitable means may be provided for rotating the shaft 4 and the associated devices, but 55 as illustrated herein, (see Fig. 1), comprises a drive pulley 12 mounted upon a shaft 14 supported by a bracket 15 connected to the base 1 of the machine. For convenience, a hand wheel 16 is attached to the pulley 12 for the purpose of turning the machine over to test adjustments and to avoid breakage of parts improperly adjusted if the machine were started by the power drive. The pulley 12 may be belted to a power shaft, or, if desired, may be driven by a suitable motor. A 60 shaft 17, extending through a bearing 19 secured to the base, is operatively connected to a suitable clutch mechanism 20 at one end thereof; and the other end of the shaft 17 is provided with a keyed gear 21 adapted to mesh with a corresponding gear 22 connected to the shaft 4, to facilitate 65 the rotation thereof. The other side of the clutch mechanism 20 is attached to the inwardly extending end of the shaft 14 to disconnect the shaft 4 from the source of power at desired intervals. A 70 suitable controlling lever 18 is provided at the 75

upper end of the column 2, and is operatively connected to a system of levers 23 to operate the clutch mechanism. The clutch lever 18 is positioned convenient to the operator so that the machine may be stopped instantly when desired. 5

Adjacent to the column 2, and substantially at the upper end thereof, a sealing mechanism 24 adapted to reciprocate vertically and support the sealing devices, is mounted upon the column 2 by means of a suitable supporting member 25 provided with an extension 26 adapted to slidably engage a groove 27 (see Fig. 4) formed in the column 2. A bracket member 29 is attached to the supporting member 25, having a threaded aperture 28 at the upper end thereof adapted to receive a vertical shaft 30 upon which the sealing devices are rotatably mounted. The shaft 30 is threaded to the bracket member 29 and is locked in position by a suitable nut 31, so that it is adapted to move vertically with the member 25. The lower end of the shaft has a sealing anvil 32 attached thereto, which is adapted to align and to press downwardly the caps to be sealed on the containers, and to hold them in position during the sealing operation. 25

A sleeve 34 is telescoped about and rotatably mounted with respect to the shaft 30, and extends substantially along the entire length of the shaft. A ball bearing 35 is provided at the upper end of the member 25 for rotatably supporting the sleeve 30 thereon to be driven through the intermediation of a gear 36 secured thereto. The gear 36 is adapted to mesh with a gear 37 connected to the upper end of the shaft 4, whereby the sleeve 34 is rotated. It will be noted that the gear 37 is 35 substantially wider than the gear 36, whereby the sealing column 24 may be moved vertically without disturbing the relation of the gears 36 and 37.

At the lower end of the sleeve 34, above the anvil 32, a sealing head 39 is suitably secured thereto, which, preferably, comprises a suitable circular casting 40 having apertures 41 therein for pivotally mounting a plurality of spinning rollers 42. 40

In Figs. 3, 6, 7 and 9, the spinning rollers 42 and operating means are illustrated in detail. Although three spinning rollers are preferred, as shown herein, any number may be used. It is necessary to describe only one in detail, since they are alike and are operated simultaneously. The 50 roller 42 (Fig. 9) is rotatably mounted upon a shaft 44 supported by a horizontal arm 45 having a bearing 46 therein adapted to receive the shaft 44. The shaft 44 is slidably with respect to the arm 45, but is held resiliently in position by a 55 spring member 47 secured thereto at 49. The arm 45 is pivotally supported by a stub shaft 50 disposed in the apertures 41 of the casing 40, and is rotatably mounted therein to facilitate the radial oscillation of the rollers about the stub shaft with respect to the central axis of the sealing column. An auxiliary arm 51 is connected to the lower end of the stub shaft 50, and is resiliently attached to the arm 45 by means of a spring member 52 (Fig. 7) adapted to absorb any shocks when 60 the rollers are moved radially into engagement with the container to be sealed. 65

For oscillating the stub shaft, a segment of a gear 54, extending radially inwardly, is secured to the upper end of the stub shaft 50, which is 70 adapted to engage a corresponding gear 61 and is adapted, on vertical movement, to oscillate the gear 54 to move the rollers 42 toward and away from the container to be sealed. A further description of the gear 61 is given hereinafter. 75

A casing 55 is rotatably mounted above the spinning head 39 about the sleeve 34, but is adapted to slide vertically thereon. The casing 55 comprises an upper casting 56 and a lower casting 57, having flanges 59 and 60, respectively, which are adapted to be bolted together. The gear 61, meshing with the gears 54, is keyed to the lower casting 57 and is adapted to be moved vertically with respect to the gears 54 to effect rotation of the gears 54 to open and close the spinning rolls to seal the caps to containers. To facilitate the above operation, inclined gears may be utilized to rotate the stub shafts radially inwardly during relative downward movement and radially outwardly during upward movement.

It will be noted that the radial movement of the spinning rollers 42 depends upon the effective rotation between the gear 61 and the gear members 54. Since it is desirable to utilize the spinning rollers for sealing caps upon containers varying in size, the radial movement of the spinning rollers must be adjustable. To accomplish this, a device is provided for determining the proper circumferential position of the gear members prior to and after the relative movement thereof, that is, to adjust the effective position of the rollers for caps varying in diameter.

In the preferred embodiment, (see Figs. 3 and 4), there is shown a gear 62 secured to the sleeve 34 in the casing 55 provided by the flanges 59 and 60. A plurality of vertical shafts or pins 64 extend through apertures provided in the horizontal portions of the members 59 and 60, and are provided with a bolt head 65 adapted to be engaged by a wrench or other suitable tool. Pinion gears 66 are keyed to the shafts 64 within the casing, and engage the gear 62, whereby, if it is desired to rotate the casing 55 and gear 61 with respect to the sleeve 34 to adjust the rollers 42 for different sizes of containers, the shafts 64 may be rotated to turn the pinion gears 66 and the casing 55 about the sleeve 34 and gear 62. When the casing is in the desired position, the shafts 64 may be locked against accidental rotation by means of the lock nuts 67.

In Fig. 10 there is shown a slightly different device 69 for adjusting the gears 54 and 61 and the rollers 42, which device comprises an upper casting 70 and a lower casting 71, having horizontal flanges 72 and 74, respectively. The flange 72 of the upper casting is provided with circumferential slots 75 adapted to receive a plurality of bolts 76 threaded to the flange 74 of the lower casting 71. The slots facilitate the relative circumferential adjustment between the upper and lower casting members, whereby the angular position of gear 61, with respect to the gears 54, may be adjusted to give a corresponding adjustment of the spinning rollers 42 for different sizes of containers. The modified construction eliminates the use of gears 62 and 66, and simplifies the adjustment for different sizes of containers.

In the preferred embodiment and in the construction shown in Fig. 10, the effective position of the gear 61 with respect to the segmental gears 54 is adjusted in a similar manner. In both instances, the gear 61 may be advanced or rotated in a clockwise direction whereby the gears 54 oscillate the rollers radially inwardly to facilitate engaging a smaller size cap. Upon operation of the head, the gear 61 will engage gears 54 and rotate them inwardly said predetermined distance, but, by reason of the adjustment, the oscillation takes place further radially inwardly. Likewise, if a larger size cap is to be sealed upon

a container, the gear 61 may be retarded or rotated in a counter-clockwise direction, whereby the gears 54, operating the rollers 42 oscillate further radially outwardly.

Referring again to Fig. 3, an annular recess 77, adapted to receive a suitable collar 78 rotatably secured thereto, is provided in the upper part 56 of the casing 55. To facilitate rotation of the member 56 therein, the collar 78 about member 56 is provided with an oil cup 79 for lubricating the recess 77. Preferably, a rod 80, for vertically reciprocating the casting, is slidably disposed in a suitable aperture or recess 81, provided in the column supporting member 25, and is resiliently retained therein by a spring 15 member 82. The lower end of the rod is coupled to the collar 78 at 83 and a cam roller 84 is provided at the upper end of the rod adapted to engage a suitable cam 85, which is rotated, by means of the shaft 4, at desired intervals controlled by the suitable clutch described hereinafter. In this manner, the casing 55 and associated devices are adapted to be moved vertically with respect to the sleeve 34 to operate the spinning rollers 42 to seal the containers presented, while at the same time, the casing is rotating together with the sleeve 34 about the shaft 30.

To facilitate the vertical movement of the entire sealing column 24 including the spinning rollers 42, there is provided a cam roller 86 pivoted to the member 25 adapted to engage a cam 87 which is rotatable with the cam 85. Since the surfaces of the cams 85 and 87 are not alike, the column 24 and the casing 55 and gear 61 are adapted to be reciprocated independently of and relatively to each other, whereby the cam 85 will effect the desired operation of the sealing devices as described hereinafter.

Referring more particularly to the cam constructions (see Figs. 3 and 4), there is shown a bearing 8 telescoped about the member 9 secured to the column 2, about which the cams 85 and 87 are mounted and adapted to be rotated. Preferably, the sealing column reciprocating cam 87 comprises a cylindrical cam provided with a dwell 45 88 wherein the roller 86 rides to reciprocate the sealing column. The operating cam 85, for the spinning rollers 42, is supported by the cam 87 and is bolted thereto in a predetermined manner so that the cams are effective to cooperate with each other at the beginning of and throughout the sealing operations. Preferably, the cam 85 comprises a disc member having a downwardly depending cam surface 89 against which the roller 84 of the arm 80 is held by the spring 82.

In Figs. 3 and 4, there is illustrated a clutch mechanism for controlling the cams 85 and 87 comprising a disc member 90 which is bolted to the gear 37 and keyed to the shaft 4 to rotate therewith. The disc member 90 is provided with a plurality of slots 91 adapted to engage a suitable member 92 slidably mounted upon the upper cam member 85. It will be noted that when the extension 92 is in engagement with one of the slots 91, the cams 85 and 87 are connected to and 60 rotate with the shaft 4. Since it is desirable to rotate the cams through one complete cycle for each sealing operation, so that the cams are always effective at the start of the cycle, it is necessary to disengage the slideable extension at the 70 end of each complete revolution. To accomplish this, a suitable vertical reciprocating lever 93 is slidably mounted on column 2 and is operated by a system of levers 94 connected to a foot pedal 95 or any other suitable controlling lever. An in-

volute cam segment 96 is secured to the upper end of the lever 93, which is adapted to engage a circumferential depending portion 97 of the extension 92, to move the extension radially outwardly. In this manner, when the cams 85 and 87 have completed one revolution, the wedge-shaped cam 96 moves the extension 92 out of engagement with the disc 90, whereby rotation of the cams 85 and 87 ceases, unless the foot pedal has been held down, to repeat the sealing cycle. A suitable spring 98 returns the levers 93 and 94 and the cam 96 to their original position when the foot pedal 95 is released. In order to prevent rotation of the cams after they have been disconnected from the drive shaft by means of the clutch, a wedge-shaped member 103 is bolted to the upper end of lever 93 and is adapted to act as a brake against a corresponding wedge-shaped member 109 bolted to the cam 85, whereby the cams are stopped when they have completed one revolution.

If it is desired to seal a container, the operator, by pushing the foot pedal 95 downwardly, pulls the lever 94 downwardly and moves the involute cam segment 96 out of engagement with the depending portion 97, whereby the spring member 99 pushes the extension radially inwardly to engage the succeeding slot 91. The chief advantage of having several slots, is that the extension 92 moves into engagement with the rotating disc 90 almost immediately when it is released, thus eliminating delay in starting the operation of the sealing devices. Although four slots are shown herein, any desired number may be utilized with similar beneficial results.

Substantially below the sealing devices, there is provided the platform 100 (see Fig. 1) adapted to support the containers to be sealed. The platform, preferably, is mounted upon an adjustable rod or support 101 connected to the column 2 by a pair of bracket members 102. The lower end of the sleeve is supported upon a rod 104 threaded into a suitable sleeve 105 bolted to the base 1. A hand wheel 106 is keyed to the rod 104, whereby the rod may be rotated to raise and lower the rod 101 to adjust the height of the table. Preferably, the platform 100 is resiliently mounted upon the rod 101 through the intermediation of a spring 107 to minimize container breakage.

Fig. 5 illustrates, in detail, a preferred construction for centering the containers with respect to the sealing means. This device comprises a bracket 108 bolted to an upright extension secured to the table 100. The end portions 110 of the bracket 108 are bent transversely inwardly with respect to each other and are provided with threaded apertures 111 adapted to receive bolts 112 which extend radially inward toward the container. The bolt members 112 are adapted to be adjusted to compensate for containers of different sizes by means of the lock nuts 113.

In the operation of the machine, adjustments are first made for the size of the containers to be sealed. The height of the platform 100 is adjusted to take care of the height of the containers, and the bolts 112 are adjusted for centering the containers. The gear 61 is adjusted by gears 64 (Fig. 3) to accommodate the diameter 70 of the cap and container to be sealed. Thereafter, it is advisable to turn the machine over by the hand wheel 16 through at least one cycle to see if all the parts move freely. This test is made while both the clutch 20 is effective and the 75 foot pedal 95 is pushed downwardly. If the ad-

justments are satisfactory, the clutch 20 is released and the motor or other source of power is started to rotate the drive pulley 12. The hand lever 18 is then pulled downwardly to make the clutch 20 again effective and to rotate the 5 shaft 4, by means of the bevelled gears 21 and 22. Shaft 4 in turn rotates gear 37 which meshes with gear 36 to rotate the sleeve 34, the casting 55 and the spinning head 39.

The caps are then usually placed loosely upon the containers by the operator, or, if desired, may be applied by any suitable automatic cap feeding mechanism. After a cap has been applied upon a container, the container is placed on the platform 100 and is aligned with respect 15 to the sealing anvil 32 by means of the bolt members 112. The foot pedal 95 is then pressed downwardly to operate the levers 93 and 94 and to release the extension 92 which then slides into engagement with a slot 91 of the disc 90, and starts 20 the rotation of the cams 85 and 87. Cam 87 is at once effective to move the sealing column 24 downwardly till the sealing anvil 32 rests upon the top of the cap and holds it securely upon the container. When the anvil has reached this 25 position, the cam 85 becomes effective to move the rod 80 and the casting 55 and gear 61 downwardly, whereby the inclined gear teeth of gear 61 rotate gear 54 to move the spinning rollers 42 radially inwardly against the jar and cap to be 30 sealed. It will be noted that while the above operations are performed, the spinning head 39 is rotating continuously, and when the rollers are forced against the skirt of the cap by the gears 61 and 54, they constrict the lower edge of the skirt 35 of the cap inwardly under the shoulder of the container. When the spinning rollers are brought into their ultimate sealing position and the cap is sealed, the cam 85 raises the casting 55 to move the gear 61 upwardly to oscillate the roller 40 supporting devices outwardly and out of engagement with the cap, and the cam 87 is effective to raise the entire sealing column upwardly and away from the sealed package till it reaches its original position. The wedge-shaped cam 96, 45 upon the completion of the revolution becomes effective to move the extension 92 out of engagement with the slot 91, and the rotation of the cams 85 and 87 ceases. The sealed package is then removed and another is presented and the 50 cycle of operation is repeated by again actuating the foot pedal 95. If the machine is to be stopped instantly, the hand lever 18 is moved upwardly to throw out the clutch 20.

As illustrated in the present embodiment, the 55 sealing operations are upon a band cap, but it will be understood that the machine may readily be utilized for sealing other types of caps with slight changes therein. In some instances, it may be desirable that the spinning rollers be 60 replaced by rollers which are adapted to reform a bead in a cap to constrict a rubber gasket or the like. This is easily accomplished as the rollers are interchangeably mounted upon the spinning head. If different sizes of caps are to 65 be applied, the spinning rollers may be adjusted by the device shown either in Fig. 4 or Fig. 10.

It will be seen that the present invention provides an improved sealing machine which is adapted to seal either band caps or friction caps 70 provided with a constrictable bead upon containers. The machine can be operated very rapidly, and is adapted to provide a secure seal upon the containers without breakage thereof. The cam devices and the spinning rollers are 75

readily adjustable to compensate for the size of caps and containers, and cooperate to attain the above advantages. The cam actuating clutch is simple in construction and insures the positive

5 operation of the cams at the beginning of the sealing cycle whenever a cap is sealed upon a container. The present machine is rugged in construction, and can withstand the rough usage to which it may be subjected. The operating and 10 maintenance costs are reduced to a minimum, since one man can readily operate the machine and the parts thereof are not subjected to any great sealing strains, whereby very little power is required.

15 As various changes may be made in the form, construction and arrangement of the parts herein without departing from the spirit and scope of the invention and without sacrificing any of its advantages, it is to be understood that all 20 matter herein is to be interpreted as illustrative and not in a limiting sense.

Having thus described my invention, I claim:

1. In a sealing machine, the combination of 25 rotatable means, spinning rollers mounted on said means, said spinning rollers being adapted to oscillate inwardly a predetermined distance, and gear means for oscillating said rollers inwardly and outwardly to seal a cap upon a container, said gear means being rotatably adjustable to position said rollers for different sizes of 30 containers without changing the distance said rollers oscillate.

2. In a sealing machine, the combination of a 35 supporting member, means for rotating said supporting member, a plurality of spinning rollers movably mounted on said supporting member, a gear having inclined teeth thereon operatively connected to said spinning rollers, and means for moving said gear axially to move said spinning 40 rollers inwardly, to seal a cap upon a container.

3. In a sealing machine, the combination of a 45 rotatable member, a supporting member on the end of said first member, a plurality of spinning rollers mounted on said supporting member, gears operatively connected to said spinning rollers, a gear adapted to engage and position said gears 50 connected to said spinning rollers to adjust the position of said rollers, means for moving said last gear upwardly and downwardly to oscillate said gears and rollers inwardly and outwardly, and means for changing the circumferential position of said last gear to predetermine the position at which said rollers are oscillated inwardly and outwardly.

55 4. In a cap spinning machine, the combination of a supporting member, a plurality of means adapted to constrict a closure cap upon a container, means for supporting said first means, gear members operatively connected to said first means, a gear positioned radially with respect to 60 said gear members and adapted to engage and oscillate said gear members and said constricting means inwardly, and means above said supporting member adapted to change the relative positions of said gear members to determine the path of movement of said constricting means for accommodating different sizes of caps.

65 5. In a sealing machine, the combination of a 70 drive shaft, a member on said shaft having a recess therein, a sealing head operatively connected to said drive shaft, said sealing head having a plurality of spinning rollers thereon, a cam member mounted on said shaft operatively connected to said rollers, a clutch mechanism secured to said cam provided with a slid- 75

ber adapted to engage the recess in said first member to make said cam effective to operate said spinning rollers, and a second cam normally in the path of said slideable member adapted to engage said slideable member upon the completion of one revolution to move outwardly from said shaft. 5

6. In a sealing machine, the combination of an upright column, a sealing head adjacent to said column, a rotatable shaft in said column, a member on said shaft having a plurality of recesses in the outer periphery thereof, a rotatable member mounted about said shaft, means slidably connected to said rotatable member adapted to engage one of said recesses in said first member, 15 to make said rotatable member rotatable with said shaft, means secured to said rotatable member and operatively connected to said sealing head for operating said sealing head, and means for moving said slideable means out of engagement 20 with said recess when said shaft has completed substantially one revolution.

7. In a sealing machine, the combination of an upright column, a sealing head adjacent to and slidably mounted on said column, a rotatable shaft 25 on said column, a member secured to said shaft having recesses in the outer periphery thereof, a rotatable member mounted above said shaft, means slidably connected to said rotatable member adapted to engage one of said recesses in said 30 first member to connect said rotatable member rotatably therewith, a cam secured to said rotatable member and operatively connected to said sealing head for raising and lowering said sealing head, and means for moving said slideable 35 means out of engagement with said recess when said shaft has completed one revolution.

8. In a sealing machine, the combination of an upright column, a sealing head adjacent to and slidably mounted on said column, said sealing head 40 being provided with a plurality of spinning rollers, a rotatable shaft in said column, a member secured to said shaft having a plurality of recesses therein, a rotatable member mounted above said shaft, means slidably connected to said rotatable 45 member adapted to engage one of said recesses in said first member, to connect said rotatable member rotatably therewith, a cam secured to said rotatable member for raising and lowering said sealing head, a second cam secured to said first 50 cam, means operatively connecting said second cam and said spinning rollers, whereby said second cam is effective to move said spinning rollers radially inwardly and outwardly, and means for moving said slideable means out of engagement with said recess after one revolution has been completed. 55

9. In a sealing machine, the combination of a 60 rotating sleeve, means on said sleeve for mounting a spinning tool, and a pair of gears having inclined teeth thereon for operating said spinning tool by axial movement thereof, said gears being adapted to adjust the position of said spinning tool for different sizes of containers by circumferential adjustment of their position. 65

10. In a sealing machine, the combination of a 70 supporting member adapted to be rotated continuously, a plurality of spinning rollers mounted upon said supporting member, said spinning rollers being adapted to oscillate inwardly to engage and seal containers, a gear axially movable to move said rollers inwardly to seal a container and rotatably adjustable to position rollers for different sizes of containers. 75

11. In a sealing machine, the combination of a supporting member, means for rotating said supporting member, a plurality of spinning rollers movably mounted on said supporting member, a gear having inclined teeth thereon operatively connected to said spinning rollers, means for moving said gear axially to move said spinning rollers inwardly for sealing a container, and means for rotating said gear to adjust the position of said rollers for different sizes of containers.
12. In a sealing machine, the combination of a supporting member, a plurality of spinning rollers pivotally mounted on said supporting member, a gear operatively connected to each of said spinning rollers, said gears having inclined teeth thereon, means for rotating said supporting member and said spinning rollers, means for lowering said supporting member into position over a container, and a gear having inclined teeth thereon adapted to engage each of said first gears and rotate said first gears upon downward movement of said supporting member to move said spinning rollers inwardly to engage a closure cap on the container and seal it thereto.
13. In a sealing machine, the combination of a sleeve, means for rotating said sleeve, a supporting member mounted on said sleeve, a plurality of spinning rollers mounted on said supporting member, a cam for raising and lowering said sleeve, a gear member operatively connected to each of said spinning rollers and a second cam for oscillating said gear members whereby said gear members move said spinning rollers inwardly to engage and seal a closure cap.
14. In a sealing machine, the combination of a rotating sleeve, a supporting member on the end of said sleeve, a plurality of spinning rollers mounted on said supporting member, a gear having spiral teeth thereon, gears operatively connected to said spinning rollers in mesh with said spiral gear, means for moving said spiral gear axially to move said rollers inwardly and outwardly, and means for rotating said spiral gear to determine the distance said rollers are moved inwardly and outwardly, thereby to accommodate various sizes of containers.
15. In a sealing machine, the combination of a rotatable sleeve adapted to operate a sealing head, a gear secured to said sleeve having inclined teeth thereon adapted to position the spinning roller, a shaft mounted adjacent to said sleeve, a corresponding gear secured to said shaft adapted to engage said first gear, and an arm connected to said second shaft for supporting a spinning roller, said arm being adapted to oscillate inwardly with respect to said shaft upon relative movement of said gear members.
16. In a sealing machine, the combination of a rotatable shaft, a gear member secured to said shaft, a supporting member mounted on and rotatable with said shaft, a plurality of stub shafts mounted on said supporting member, gear members secured to said stub shafts adapted to engage said first gear, and arms connected to said stub shafts having spinning rollers at the free ends thereof, said rollers being adapted to be moved into effective position upon relative movement of said gear members.
17. In a sealing machine, the combination of a rotatable sleeve, a gear secured to said sleeve having inclined teeth thereon, a plurality of shafts mounted adjacent to said sleeve, corresponding gear members secured to said shafts adapted to engage inclined gear teeth, and means on said shafts for supporting spinning rollers adapt-
- ed to be moved into effective position at desired intervals by relative movement of said gear members.
18. In a sealing machine, the combination of a supporting member mounted upon a rotatable shaft, a spinning roller, means operatively connecting said roller to said supporting member, gear members for oscillating said means, and means above said supporting member adapted to change the relative position of said gear members whereby the effective oscillation of said roller may be adjusted.
19. In a cap spinning machine, the combination of a supporting member, a plurality of spinning rollers, means for supporting said rollers, gear members operatively connected to said means, a rotatable gear adapted to engage said gear members to oscillate said means and move said rollers inwardly, and means above said supporting member adapted to change the relative positions of said gear members to determine the path of movement of said rollers for accommodating different sizes of articles.
20. In a capping machine, the combination of a rotatable shaft, a supporting member on said shaft, a plurality of spinning rollers, means for rotatably mounting said spinning rollers on said supporting member, gear members secured to said means, and a corresponding gear member secured to said shaft adapted to engage said gear members and oscillate said spinning rollers, said supporting member being adjustably secured to said shaft to change the effective positions of said gear members and the initial and final positions of said rollers.
21. In a capping machine, the combination of a vertical rotatable drive shaft, a gear member of substantial width at the upper end of said shaft, a column adjacent to said shaft, a rotatable sleeve slidable with respect to and supported by said column, a second gear member secured to said sleeve adapted to engage said gear on said drive shaft, said second gear being narrower than the said first gear, a supporting member at the lower end of said sleeve, means for moving said head upwardly and downwardly with respect to said sleeve, spinning rollers mounted on said supporting member, and means for oscillating said spinning rollers into effective position when said head is moved downwardly, said gears being slidable with respect to each other and adapted to remain in engagement during relative vertical movement between said shaft and sleeve.
22. In a sealing machine, the combination of a rotatable drive shaft, a supporting head adjacent to said drive shaft, spinning means mounted upon said head, a cylindrical cam mounted on said drive shaft adapted to reciprocate said head in a vertical direction to drop it into effective sealing position, a second cam mounted above said first cam, and means operatively connecting said rollers to said second cam adapted to oscillate said spinning means with respect to said head.
23. In a sealing machine, the combination of a rotatable drive shaft, a supporting head operatively connected to said drive shaft, spinning means mounted upon said head, a cylindrical cam mounted on said drive shaft adapted to reciprocate said sealing head in a vertical direction, a second cam mounted above said first cam, means operatively connecting said spinning means and second cam adapted to oscillate said spinning means with respect to said head, and a clutch mechanism attached to said second cam

adapted to engage said drive shaft to make said cams effective.

24. In a sealing machine, the combination of a rotating sealing means having spinning rollers thereon and inclined gears associated with said means for operating said rollers and for adjusting the position of said rollers by rotary movement of said gears, means for supporting a container beneath said sealing means, and means for moving one of said means relatively with respect to the other of said means to place said rollers in operative position with respect to a cap on the container.
- 10 25. In a sealing machine, the combination of a supporting member, a plurality of spinning rollers mounted upon said supporting member, said spinning rollers being adapted to oscillate inwardly to engage and seal a cap on a container, a gear axially movable to move said rollers inwardly to seal a container and rotatably adjustable to position said rollers for different sizes of containers, a member for supporting a container and means for moving one of said members toward the other of said members to place 20 said rollers in sealing position with respect to the cap on the containers.
- 25 26. In a sealing machine, the combination of a rotatable sleeve, a member mounted on said sleeve, a plurality of spinning rollers, shafts on said member for supporting said rollers, inclined gear segments on said shafts for oscillating said rollers, an inclined gear telescoped over said sleeve for operating said gear segments, a supporting member for mounting said gear on said sleeve, said sleeve being rotatable

with respect to said last member, a gear secured to said sleeve, and a second gear carried by said last member engaging the gear secured to the sleeve, said second gear being adapted to be rotated to rotate said first gear, said last member and said inclined gear to change the circumferential position of said inclined gear with respect to said gear segments.

27. In a sealing machine, the combination of a rotatable sleeve, a member mounted on said sleeve, spinning rollers supported by said member having gear segments operatively connected thereto, a gear for engaging said gear segments, a collar for supporting said gear, a second collar secured to said first collar having circumferential slots therein, and bolts extending through said slots and threaded into said first collar to attach said collars together, said bolts being adapted to be loosened to move said collars circumferentially with respect to each other, 15 to change the circumferential position of said gear with respect to said gear segments.

28. In a sealing machine, the combination of a supporting member mounted upon a rotatable shaft, sealing devices operatively mounted on 25 said member, gear members operatively connected to said sealing devices, a gear for engaging said gear members to move said sealing devices into and out of effective position, a collar for supporting said gear, and a second collar connected 30 to said first collar, said collars being adapted to be moved circumferentially with respect to each other to adjust the relative position of said gear with respect to said gear members.

ABRAHAM PODEL. 35
